No. 718,402.

PATENTED JAN. 13, 1903.

E. G. TUFTS.
SHIPPING CRATE.
APPLICATION FILED FEB. 8, 1902.

NO MODEL.

UNITED STATES PATENT OFFICE.

ELMER G. TUFTS, OF AURORA, INDIANA.

SHIPPING-CRATE.

SPECIFICATION forming part of Letters Patent No. 718,402, dated January 13, 1903.

Application filed February 8, 1902. Serial No. 93,177. (No model.)

To all whom it may concern:

Be it known that I, ELMER G. TUFTS, a citizen of the United States, residing at Aurora, in the county of Dearborn and State of Indiana, 5 have invented certain new and useful Improvements in Shipping-Crates; and I do hereby declare the following to be a full, clear, and exact description of the invention, such as will enable others skilled in the art to which 10 it appertains to make and use the same.

My invention has relation to shipping-crates, and more particularly to crates designed, primarily, for shipping small fruits, as berries or the like; and it consists of certain 15 novel features of combination and construction of parts, the preferred form whereof will be hereinafter fully set forth, and illustrated in the accompanying drawings.

The prime object of my invention is to provide 20 a shipping-crate which will consist of a plurality of individual sections or receptacles which may be very expeditiously and cheaply manufactured and quickly assembled in operative combination, the parts of one individual crate being so formed and shaped as to readily receive and coöperate with a contiguous 25 part of the next adjacent section.

A further object is to provide simple and cheap though reliably efficient means for locking 30 or holding the several crate-sections when combined together.

Other objects and advantages will be made 35 clearly apparent from the following specification, considered in connection with the accompanying drawings, in which—

Figure 1 is a perspective view of my improved shipping-crate complete, showing a number of nest-sections assembled together. Fig. 2 is a perspective detail view showing 40 one of the crate-sections separated. Fig. 3 shows two of the sections assembled together, the top section carrying the lid, which is secured direct thereto. Fig. 4 is a perspective view showing part of end with upper part 45 broken away. Fig. 5 is a detail of preferred fastener.

In order to conveniently refer to the several features of my invention, numerals will be employed, of which 1 designates the side sections, while 50 2 indicates the end sections, form-

ing my improved crate, it being understood that said parts may be made of any preferred size and of any material deemed suitable for the purpose. The side sections are connected together by the uprights 3, while the end sections 2 are similarly reinforced and supported by the members 4. I desire to call particular attention to the construction of said members 4, inasmuch as it will be observed that the upper ends thereof are provided upon their 55 inner corners with the recess 5, while the lower ends thereof are provided upon their outer corners or ends with the recesses 6, and it is therefore obvious by reference to Fig. 1 that the upper recesses 5 will receive the depending 60 ends 7 of the next section above, thus causing said end sections or members 4 to partially overlap each other and insure that the upper section will be held against any lateral movement. 70

Since the depending ends 7 of the members 4 will reach down in the recess 5, said extended end will rest directly against a contiguous part of the end boards or sections 2, and thereby hold the upper crates against longitudinal 75 movement.

The floor-sections 8 reach from end to end and are secured directly to the upper edge of the lower end section 2 by screws or nails, and said floor-sections are therefore disposed 80 substantially in the middle portion of each crate-section instead of being disposed upon the bottom side thereof, as is common. By this arrangement of the floor-sections 8 I am enabled to place a row of boxes or the like 85 so that they will rest above the surface of the next lower section sufficiently to insure that said boxes will protrude upward until they are level with the top of each section. The floor-sections are designed to form covers 90 therefor and prevent the berries or the like from casually slipping out of the boxes.

It will of course be understood that the usual form of covers may be employed for the boxes, if preferred, though the location 95 of the sections 8 may be such as to insure that one row of boxes will be covered by each section. It is therefore clear by the construction above described that any one whether skilled in the use of tools or not may readily 100

form my improved shipping-crate from any suitable variety of lumber or boards, and by providing the recesses 5 and 6 in the members 4 a locking device which will hold the 5 independent sections against relative movement will be provided.

In order that the several independent sections may be built up or nested with each other and secured against casually falling out 10 of place should the entire number of assembled crates be turned upon end, I provide the locking-bails 9, one for each end of each independent crate, said bails being formed of wire of suitable diameter properly bent, as 15 indicated, and secured in place in any preferred way, as by the staple 10. The said bails are substantially V-shaped and are of sufficient length to reach downward to the middle of the next contiguous crate and be 20 engaged by the rotatable keeper or hook 11, as clearly indicated.

In Fig. 1 I have shown the lid 12 as being attached to a strip 13 by hinges 14 or the equivalent, said strip 13 being nailed upon 25 the top of one crate-section, while in Fig. 3 I have shown the lid and the strip 13 as being differently mounted in position, inasmuch as it will be seen that the upper half of one of the independent crate-sections is removed 30 and said strip 13 attached thereto, thus insuring that the lid 12 will not rest directly upon the berries, yet retain them in position in the receptacles provided therefor.

It will be understood that a portion of the 35 top section may be removed, together with the floor-sections 8, the said floor-sections to be replaced by directly connecting the lid to the frame portion thus left, as shown in Fig. 3, though I prefer to employ the construction 40 illustrated in Fig. 1 and leave the floor-sections in place and attach the lid a proper distance above said floor-sections, so as to leave space for other crates full of berries to be disposed thereon. By the arrangement of my 45 improved crate construction each of the berry or fruit boxes may be filled heapingly full, and the upper berries will be in no wise damaged by contacting with the lid or with the underside of the next adjacent floor-sections. 50 In Figs. 4 and 5 I have illustrated the preferred form of fastening device which I wish to employ in holding two or more crates in combination with each other, wherein it will be observed that the bail 9 is designed to co- 55 operate with the form of catch or fastener illustrated in detail in Fig. 5. The said fastener or keeper comprises the stem 15, designed to be seated in a suitable aperture in one of the end sections and being formed of 60 a suitable piece of wire is bent downward and upward to provide the loop-sections 16, while the free end of the wire is bent upon itself to provide the finger 17, which being in the form of a hook, as illustrated in Fig. 65 5, is designed to engage the middle portion of the bail 9 and hold the same securely in

place. When it is desired to release the bail, the loop member 16 may be moved laterally and upward, thereby bringing the finger 17 so that it will point downward, and thus enable 70 the bail to be slipped out of engagement therewith. The stem 15 is designed to extend entirely through an aperture provided in one of the end sections and is then provided with a washer 18, when by upsetting 75 the end of the stem 15 the same will be reliably held in place, whereby the same may be freely rotated, but cannot be withdrawn. I reserve the right to locate my improved form of securing device differently from what I 80 have herein illustrated in Fig. 1, inasmuch as the bail may, for instance, be carried by the top end section, as shown in Fig. 4, of one of the individual crates and extended upward into engagement with the keeper or 85 finger 17, which latter is carried by the next adjacent end section of the crate above.

By the construction just described for the several independent crate-sections it is obvious that a shipping-crate of any preferred 90 size may be readily built up by assembling any desired number of said independent sections together. All of the said independent sections being readily interchangeable leaves it a matter of no importance as to where any 95 of the independent sections should be located during the assembling process. While I have described the preferred construction of the various details, I wish to comprehend in this application all substantial equivalents and 100 substitutes therefor.

Having thus fully described my invention, what I claim as new, and desire to secure by Letters Patent, is—

1. The herein-described shipping-crate 105 comprising a plurality of independent crate-sections each formed substantially in the manner specified and provided at each end with the members 4 having the recesses 5 and 6 at their outer and inner corners respectively 110 adapted to intermesh with each other whereby the independent sections will be held against lateral and longitudinal movement, in combination with locking-bails 9 adapted to engage a keeper carried by the next contiguous section and suitable lid-sections secured to one of the independent sections 115 adapted to form the top of the assembled crates, all substantially as specified and for the purpose set forth.

2. In a shipping-crate, a plurality of independent crate-sections comprising separated ends and sides and intermediate floor supported upon the upper edge of the lowermost of the ends and vertically-disposed reinforcing members 4 secured to said ends and provided at their upper ends upon their inner corners and at their lower ends upon their outer corners with recesses, the depending portions formed by the lowermost recesses 125 adapted to engage the recesses at the upper ends of said members on the next lowermost 130

crate, pivoted bails on the lowermost end piece of one crate and coöperating means on the uppermost end piece of the next adjoining crate, and a strip secured to the uppermost crate and having a hinged lid carried by said strip, all substantially as herein shown and described.

In testimony whereof I affix my signature in presence of two witnesses.

ELMER G. TUFTS.
